PUSHER FOR TOW LINES

Mario Thomas Sgriccia, Detroit, Mich., assignor to Rapistan-Keystone, Inc., Detroit, Mich., a corporation of Michigan

Filed Nov. 10, 1960, Ser. No. 68,549

6 Claims. (Cl. 104—172)

This invention relates to a pusher for tow lines, and more particularly to a pusher for tow lines which releases on overload.

In industrial installations it is common to have an overhead conveyor drive to which is connected pusher mechanism arranged to engage the upright masts of floor trucks for moving them along the floor. One of the problems encountered in this type of conveying is that the wheels of the truck will engage articles which have inadvertently become placed in the path of the truck and cause the truck to stop. When this occurs the overhead conveyor drive continues to operate and either the mast of the floor truck is broken off or damaged or the overhead conveyor drive is broken or damaged.

The present invention overcomes these problems by providing a pusher which releases on overload. If the floor truck stops for any reason, the pusher will release the floor truck mast and the overhead conveyor drive can continue without damage to the floor truck, pusher or overhead conveyor drive.

It is therefore an object of this invention to provide a pusher for tow lines which releases automatically on overload.

Another object of this invention is to provide a pusher for tow lines which is constructed of a minimum number of parts and is therefore economical to manufacture and maintain.

Another object of this invention is to provide a pusher for tow lines which has a blocker element to prevent escape of a floor truck mast should it accelerate ahead of the pusher.

These and other objects and advantages of this invention will become apparent upon reading the specification in conjunction with the accompanying drawings.

In the drawings:

FIG. 1 is an exploded view of the pusher for tow lines showing the components thereof in perspective.

FIG. 2 is a side elevational view of the pusher for tow lines.

FIG. 3 is a plan view of the pusher for tow lines showing a portion thereof cutaway.

This invention relates to a pusher which is adapted to be secured to an overhead conveyor drive such as a monorail conveyor. The pusher includes a support plate which is adapted to be secured to the overhead conveyor drive. A pair of pusher members are pivotally connected to the support plate and suspended there beneath. The pusher members have guide portions and segments which are offset inwardly from the guide portions forming abutment portions and gate portions. The pusher members are connected to the plate in a manner such that surfaces of the gate portions are normally in contact with each other or in the closed position. The guide portions of the pusher member are adapted to direct the mast of a floor truck into the pusher and guide the mast to a position wherein it engages the abutment portions. Flanges are provided on the gate surfaces and a tension spring connected therebetween.

The spring constantly urges the gate surfaces into contact with each other. Under normal operating conditions the tension spring is sufficient to hold the gate surfaces in the closed position. However, if an excessive force is applied to the floor truck mast the spring will yield. The pusher members pivot about a base plate providing for

2

separation of the gate surfaces and allowing passage of the floor truck mast. A blocker member is associated with the guide surfaces and functions to allow the mast of the floor truck to enter; however, if the floor truck accelerates ahead of the overhead conveyor during the conveying operation, the blocker element prevents withdrawal of the mast.

The tow line pusher assembly is designated generally as 10. The assembly includes the support plate 15, the pusher members 20 and 30, the pivot pins 27 and 37, the blocker 45 and the tension spring 50.

Referring now more specifically to the details of the invention, FIG. 1 shows an exploded view of the tow line pusher assembly 10 and the support plate 15 now to be described.

The support plate 15 is a generally rectangular plate-like member. It is provided with a pair of apertures 16 and 17 which extend transversely therethrough. The apertures 16 and 17 are spaced centrally of the longitudinal extent of the member and inwardly from the side edges thereof. These apertures are adapted to receive the pivot pins 37 and 27 respectively for purposes which will be explained more fully hereinafter. The support plate 15 is provided with appropriate fastener means (not shown) for securing the support plate to an overhead conveyor drive or tow line.

A pusher member 20 is positioned beneath the support plate 15 and pivotally connected thereto in a manner which will become more evident subsequently. The pusher plate 20 has a guide surface portion 21 with an exposed end portion 22 which is rolled outwardly. The pusher member 20 also has an offset segment which includes an abutment portion 23 and a gate portion 24. The abutment portion 23 is offset inwardly and is disposed at an oblique angle with respect to the guide portion 20. The gate portion 24 is parallel with the guide portion 20 but is offset inwardly therefrom. An L-shaped flange 25 is secured to the end of the gate portion 24 and projects outwardly therefrom. The flange 25 serves as an anchor point for one end of the spring 50 to be explained more fully hereinafter. A sleeve-like pivot pin bracket 26 is secured to the outer surface of the abutment portion 23 by means such as weldment. The pivot pin bracket 26 is adapted to receive the pivot pin 27.

45 A stop 29 is secured to the guide portion 20 of the pusher member 21 and is positioned inwardly from the rolled end 22 toward the abutment portion 23. The purpose of the stop 29 will be explained more fully hereinafter.

50 A pusher plate or member 30 is also positioned beneath and pivotally connected to the support member 15 adjacent the pusher member 20. The pusher member 30 is a mirror image of the pusher member 20 and has a guide portion 31 with a rolled end 32, an abutment portion 33 and a gate portion 34. The abutment portion 33 and the gate portion 34 are offset inwardly from the guide portion 31. An L-shaped flange 35 is secured to the gate portion 34 and serves as an anchor point for the other end of the tension spring 50.

60 A sleeve-like pivot pin bracket 36 is secured to the outer surface of the abutment portion 33. It receives the pivot pin 37.

A stop 39 is secured to the inside surface of the guide portion 31 and is spaced inwardly from the rolled end 32 toward the abutment portion 33. The stop 39 is directly opposite the stop 29 on pusher member 21.

The pusher member 20 is pivotally connected to the support plate 15 by the pivot pin 27. The pivot pin 27 is received within the bracket 26 and secured thereto by any well-known fastening means. The pivot pin 27 projects above the bracket 26 and through the aperture 17 formed in the support plate 15. A washer-like collar

28 slides over the pivot pin 27 and the top of the pivot pin is provided with a cotter pin or lock pin (not shown).

The pusher member 30 is pivotally connected to the support plate 15 by the pivot pin 37. The pivot pin 37 is received within the bracket 36 and fixed thereto in any well-known manner. The pivot pin 37 projects through the aperture 16 in the support plate 15 and receives a collar 38 thereover. The top of the pivot pin 37 is provided with a cotter pin or lock pin (not shown) which maintains the pivot pin in position.

A conventional tension spring 50 is connected between the flanges 25 and 35 continuously urging the gate portions 24 and 34 of the pusher members into contact or the closed position. The abutment portions 23 and 33 of the pusher members form a V-shaped work surface against which the mast 55 of a truck 60 abuts.

The guide portions 21 and 31 are provided with apertures adjacent the stop members 29 and 39. These apertures receive a blocker shaft 47 which is journaled therein. These apertures are of sufficient size so as to allow the pusher members 20 and 30 to freely pivot about the pivot pins 27 and 37. Washers are positioned on the blocker shaft 47 on either side of the guide portions of the pusher members to facilitate easy rotation of the blocker shaft 47. A cotter pin (not shown) is placed in the end of the blocker shaft 47 to fix it in position. One end of the blocker shaft 47 is bent to form a handle 48 which can be utilized to rotate the blocker shaft 47 to position the blocker member 45 now to be described.

The blocker member 45 is a generally rectangular plate-like member having a turned over end or lip 46. The lip 46 is secured to the blocker shaft 47 by any conventional means such as welding or threaded fasteners. As best shown in FIGS. 2 and 3 the one edge of the lip 46 abuts the stop members 29 and 39. This prevents counterclockwise rotation of a blocker 45 from the vertical position shown in FIGS. 2 and 3. However, the blocker 45 is free to rotate in the clockwise direction. The blocker 45 allows passage of the floor truck mast 55 into the pusher assembly 10, but prevents escape of the floor truck mast should the truck accelerate ahead of the overhead conveyor drive.

Operation

The overhead conveyor drive travels in the direction of the arrow A shown in FIG. 1. The support plate 15 is secured to the overhead conveyor drive by conventional fastener means and is carried therewith. To utilize the pusher assembly 10 a floor truck 60 having an upright mast 55 is positioned in the path of travel of the pusher assembly 10. As the pusher travels the blocker 45 will eventually come in contact with the mast 55 of the floor truck. This will cause the blocker 45 to rotate in a clockwise direction and allow passage of the mast into the area between the guide portions 21 and 31 of the pusher members 20 and 30.

The rolled out edges 22 and 32 of the pusher members assist in directing the mast of the floor truck to the position between the pusher members. The guide portions 21 and 31 of the pusher members continue to direct the travel of the floor truck mast 55 until it engages the abutment portions 23 and 33 of the pusher members.

The tension of the spring 50 is such that it closes the gate formed by surfaces on the gate portions 24 and 34 of the pusher members. The tension of the spring member 50 is calculated such that the forces applied by the floor truck mast to the abutment portions 23 and 33 tending to open the gate under ordinary load conditions is less than the force applied by the spring tending to close the gate. Therefore, under normal operating conditions the gate remains closed and the pusher members assume the position shown in FIG. 3.

However, should the mast 55 apply an excessive force to the abutment surfaces 23 and 33, due for instance to the floor truck engaging an obstacle in its path, the tension of the spring 50 will be overcome and the gate por-

tions 24 and 34 will pivot in a clockwise and counterclockwise direction respectively and allow passage of the floor truck mast 55 therebetween. After the mast 55 has passed from between the gate surfaces 24 and 34 the spring 50 automatically closes the gate resetting the pusher members 20 and 30 for reception of another floor truck mast.

The blocker member 45 after being rotated in a clockwise direction by contact with a floor truck mast and allowing passage of the mast rotates in the counterclockwise direction under the force of gravity. Thus, once the floor truck mast is within the pusher assembly it cannot inadvertently free itself from the pusher assembly by accelerating ahead of the overhead conveyor drive since the mast will abut the blocker 45. This arrangement is necessary where the floor over which the floor truck travels is not level and there are downwardly sloping portions. However, if the overhead conveyor drive is stopped for some reason and it is desired to release the floor truck 60 from the pusher assembly 10 it can be readily accomplished by grasping the handle 48 and rotating the blocker element 45 in the clockwise direction. The mast 55 of the truck can then move under the blocker 45 and be released from the pusher assembly 10.

The pusher assembly disclosed herein is a highly desirable device since it will release on overload preventing damage to the pusher assembly, overhead conveyor drive and the floor truck. After the pusher has released on overload it automatically resets itself so that it is entirely automatic. The device is constructed of a minimum number of component parts and is therefore economical to manufacture and maintain.

While a preferred embodiment of this invention has been described, it will be understood that modifications and improvements may be made thereto. Such of these modifications and improvements as incorporate the principles of this invention are to be considered as included in the hereinafter appended claims unless these claims by their language expressly state otherwise.

I claim:

1. A pusher for tow lines comprising; support means adapted to be secured to a conveyor drive, a pair of pusher plates pivotally connected to said support means, said pusher plates having abutment portions converging to form surfaces adapted to receive the mast of a conveyor truck, said pusher plates forming a gate therebetween adjacent said abutment surfaces, and resilient means continuously urging said gate to a closed position, excess force on said converging surfaces by said mast causing said gate to open and release said mast to prevent damage thereto.

2. A pusher for an overhead conveyor drive comprising; a support plate adapted to be secured to an overhead conveyor drive, a first pusher member pivotally connected to said support plate, said first pusher member having a segment thereof offset inwardly to form an abutment portion and a gate portion, a second pusher member pivotally connected to said support plate and having a segment thereof offset inwardly to form an abutment portion and a gate portion, flange members associated with said gate portions and spring means to urge said gate portions into contact with each other to form a closed gate, said abutment portions being convergent with respect to each other and adapted to engage the mast of a floor-truck for movement thereof, said first and second pusher members pivoting to open said gate when an excessive force is applied to said mast and closing automatically by the action of said spring means after release of said mast.

3. A pusher for an overhead conveyor drive as in claim 2 wherein said first and second pusher members have guide portions for directing said mast into engagement with said abutment surfaces.

4. A pusher for an overhead conveyor drive as in claim 3 wherein blocker means is connected to said guide sur-

faces to admit entry of said mast to said guide surfaces but prevent inadvertent withdrawal therefrom upon acceleration of said mast ahead of said conveyor drive.

5. A pusher for an overhead conveyor drive comprising; support means adapted to be secured to an overhead conveyor, generally convergent pusher means movably secured to said support means, said pusher means adapted to receive the mast of a floor-truck, said pusher means having gate means resiliently urged to the closed position, said gate means opening to release said mast on 10 overload.

6. A pusher for an overhead conveyor drive comprising; a support plate adapted to be secured to an overhead conveyor drive, a first pusher member pivotally connected to said support plate, said first pusher member having a guide portion and a segment thereof offset inwardly to form an abutment portion and a gate portion, a second pusher member pivotally connected to said support plate and having a guide portion and a segment thereof offset inwardly to form an abutment portion and 15 a gate portion, flange members associated with said gate portions and spring means positioned therebetween to 20

urge said gate portions into contact with each other to form a closed gate, said abutment portions being generally convergent and adapted to engage the mast of a floor-truck for movement thereof, said first and second pusher members pivoting to open said gate when an excessive force is applied to said mast and closing automatically after release of said mast, blocker means pivotally mounted on said guide surfaces to admit entry of said mast, and stop means secured to said guide portions and engageable by said blocker means to limit pivotal movement thereof in a direction to prevent withdrawal of said mast from said pusher upon acceleration of said mast ahead of said conveyor drive.
